US0D1075744S

(12) **United States Design Patent** (10) **Patent No.:** **US D1,075,744 S**
(45) **Date of Patent:** **** May 20, 2025**

(54) **CONVERTIBLE ELECTRONIC DEVICE**

(71) Applicant: **Intel Corporation**, Santa Clara, CA (US)

(72) Inventors: **Shantanu Kulkarni**, Hillsboro, OR (US); **Jeff Ku**, Taipei (TW)

(73) Assignee: **Intel Corporation**, Santa Clara, CA (US)

(**) Term: **15 Years**

(21) Appl. No.: **29/801,969**

(22) Filed: **Aug. 2, 2021**

Related U.S. Application Data

(63) Continuation of application No. 29/664,571, filed on Sep. 26, 2018, now Pat. No. Des. 933,060.

(51) **LOC (15) Cl.** **14-02**

(57) **CLAIM**

The ornamental design for a convertible electronic device as shown and described.

DESCRIPTION

FIG. 1 is a right, front perspective view of a convertible electronic device.

FIG. 2 is a front view of the convertible electronic device of FIG. 1.

FIG. 3 is a rear view of the convertible electronic device of FIG. 1.

FIG. 4 is a top view of the convertible electronic device of FIG. 1.

FIG. 5 is a right side view of the convertible electronic device of FIG. 1; and,

FIG. 6 is a left side view of the convertible electronic device of FIG. 1.

The broken lines in the drawings are for the purpose of illustrating portions of the convertible electronic device that form no part of the claimed design.

1 Claim, 6 Drawing Sheets
